E. A. SMITH,
BILLBOARD POSTING IMPLEMENT,
FILED OCT. 3, 1921.

Inventor
Edwin A. Smith

Attorney
A. Randolph, Jr.

Patented Mar. 6, 1923.

UNITED STATES PATENT OFFICE.

EDWIN A. SMITH, OF WOODWARD, OKLAHOMA.

BILLBOARD-POSTING IMPLEMENT.

Application filed October 3, 1921. Serial No. 505,074.

To all whom it may concern:

Be it known that I, EDWIN A. SMITH, a citizen of the United States, residing at Woodward, in the county of Woodward and 5 State of Oklahoma, have invented certain new and useful Improvements in Billboard-Posting Implements; and I do hereby declare the following to be a full, clear, and exact description of the invention, such as 10 will enable others skilled in the art to which it appertains to make use of the same.

The object of this invention is to facilitate the posting or placing of signs or posters on billboards, when the posters or signs are 15 in sheets as in the ordinary practice and particularly when each sign or poster consists of several strips of paper, some of which bear the advertisement while the other strips are plain and which strips must be 20 unrolled as they are applied, and particularly the object is to provide a means for facilitating the posting of signs of this type when the wind is blowing and when it is 25 difficult to perform the operation under ordinary conditions, as where the operator must depend upon his hands and the paste brush to hold the sheets in proper position.

Another object of this invention is the provision of an implement of the above 30 stated character which will be simple, durable and efficient, and which may be manufactured and sold at a comparatively low cost.

With these and other objects in view as 35 will become more apparent as the description proceeds, the invention consists in certain novel features of construction, combination, and arrangement of parts as will be hereinafter more fully described and 40 claimed.

For a complete understanding of my invention, reference is to be had to the following description, and accompanying drawings, in which:—

45 Figure 1 is a front elevation, illustrating the device that applies the sheet of paper bearing the advertisement.

Figure 2 is a fragmentary perspective view illustrating the head and portion of 50 the pole or handle of the device shown in Figure 1.

Posters are made up from sheets of paper bearing parts of the advertisement and which sheets are matched as they are applied 55 and also strips of plain or unprinted paper

are used to cover the portions of the billboard not covered by the sheets of paper bearing the advertisement.

To apply the strip of paper 19^a that bears the advertisement to the board 14, a 60 spindle 19^b is provided on which the paper may be wound and one end of the spindle is passed through aligned openings 21 formed in the side walls of a channel iron head 21^a and the latter is secured to one side face of 65 a pole or handle 21^b. The spindle 19^b after passing through the openings 21 rests on an angle iron bracket 22 secured to the pole or handle directly below the head 21^a and which forms a rest or stop for said spindle. 70 The head 21^a is also provided with aligned openings 22^a that receive the spindle end 23 of a pressure roller 24. The sheet of paper 19^a is coated with adhesive as it is fed off of the spindle 19^b and the operator 75 applies pressure to said sheet of paper by a slight tilting of the device to move the roller 24 towards the board.

It is to be understood that a strip of unprinted paper or border when used may be 80 applied to the bill board first or the strips of paper bearing the advertisement may be the first to be applied to the board, depending entirely on the wishes of the operator. When applying the printed strips of paper, 85 the free end thereof may be unreeled for a short distance and attached to the bill board by adhesive before the further unreeling of the roll of paper is commenced. Then as the roll of paper is extended or moved parallel 90 with the surface of the bill board, the paste is applied in rear thereof or following the same to adhesively attach the strip of paper to the bill board surface, the roller forcing the paper smoothly against the bill 95 board.

While I have shown and described the preferred embodiment of my invention, it will be understood that minor changes in construction, combination, and arrangement 100 of parts may be made without departing from the spirit and scope of the invention as claimed.

Having thus described the invention, what I claim is:—

1. An apparatus for the purpose described comprising a pole, a head secured to the pole and having pairs of openings, and a spindle and a roller mounted in said 105 openings.

2. An apparatus for the purpose described comprising a pole, a head secured to the pole and having openings, and a spindle and a roller mounted in said openings.

3. An apparatus for the purpose described comprising a pole, a head secured to the pole and having openings, a pair of spindles extending through the openings,

and a rest secured to the pole and engaged by the spindles.

In testimony whereof I affix my signature in presence of two witnesses.

EDWIN A. SMITH.

Witnesses:

C. N. SMITH,

C. R. BLECKLEY.
